UNITED STATES PATENT OFFICE.

ALBERT L. STADERMANN, OF TERRE HAUTE, INDIANA.

DISTRIBUTING INSULATOR-BRACKET.

No. 926,906. A BUREAU OF PATENTS, U. S. PATENT OFFICE.

Specification of Letters Patent.

Patented July 6, 1909.

Application filed June 23, 1907. Serial No. 380,865.

To all whom it may concern:

Be it known that I, ALBERT L. STADERMANN, a citizen of the United States of America, and a resident of Terre Haute, county of Vigo, and State of Indiana, have invented a new and useful Improvement in a Distributing Insulator-Bracket, of which the following is a specification.

My invention pertains to the mounting of insulators for electric wires, particularly where such insulators are mounted in groups, as upon poles bearing cable terminals.

My object is to provide simple and safe means for mounting a plurality of independent insulators to which a plurality of conductors may be attached for distribution.

A specific instance for the application of my invention lies in the distribution of circuits to subscribers' premises from a telephone pole, and I have chosen this instance for illustration.

This description is accompanied by two sheets of drawings in which—

Figure 1 shows elevation of the device of my invention equipped for five pairs of conductors. Fig. 2 shows side elevation of the device of Fig. 1; Fig. 3 shows side elevation of a modification of the device of Fig. 1, the structural elements being substantially the same, but the equipment consisting of but three pairs of insulators, Fig. 4 shows the device of Fig. 1 as installed for service, Fig. 5 shows a modification of one of the structural elements of my device, Fig. 6 shows the modification of Fig. 5 as embodied in a complete device in service, and Fig. 7 shows the type of device illustrated in Figs. 1, 2, and 3, the complete device being shown attached to the cross arm of the telephone pole, instead of being attached directly to the pole itself.

Referring first to Fig. 2, the mechanical structure of my device will be made clear. Part 1 is of flat bar iron, bent into U-shape and pierced in four places 2, 2', 3, 3'. The bolts or lag screws 4, 4' attach the part 1 to the pole by passing through the holes 3, 3'. Insulators 5 may be of any preferred type, the sole requirements being an axial perforation, such as is usual in porcelain knobs, and grooves for tying the conductors, or other means for attaching conductors to the insulators. A long bolt 6 with nuts 6' is (for the assembling of the device of Fig. 2) passed first through insulators for a pair of conductors, then through the hole at 2, then through a sufficient number of insulators to

fill approximately the space between the two arms of the part 1; the bolt 6 is then passed through the hole at 2' and more insulators are threaded upon it to fill it approximately; the nut 6', with washer and locking device if desired, then is screwed in place, and the device is complete, ready to receive the conductors.

The complete device as shown in Fig. 2 is illustrated in service in Fig. 4. The cable 7 is provided with terminals within the can 7' and the paired bridle wire 8 extends from the terminals within the can 7' to the premises of the telephone subscriber. The present practice is the use of insulated wires, braided separately and twisted together, for the drop from the pole to the subscriber's premises. I have shown this construction in Fig. 4. The paired drop wire is untwisted at 8' and the two conductors are separately dead ended in grooves in the insulators 5, the ends being left of sufficient length to extend without splicing into can 7' to the terminals of the cable 7; the ends thus extending into the cable terminal are shown again loosely twisted together at 8''.

It is believed that the nature, the construction and one plan of installation and use of the device of my invention has been fully set forth. I shall now pass to modifications.

In Fig. 3 is shown a modification in assembly of the parts used in the structure of Figs. 1, 2 and 4. The sole difference lies in the use of a shorter bolt 6'', and consequently of fewer insulators upon the bolt. It will be seen that a bolt of any length within reason may be used; also that a yoke 1 of any length within reason may be used; and further that the same yoke may carry any desired number of insulators within reasonable limits, the yoke 1 being shown in Fig. 3 equipped for three pairs, and in Figs. 1 and 2 equipped for five pairs of conductors.

In Fig. 7 is shown an alternative method of installing the device of my invention upon a telephone pole. 10 is end view of a cross arm. The yoke 1 is perforated in its central portion to receive two bolts with a clearance between the bolts of $3\frac{1}{4}$ inches, that being the usual thickness of a telephone cross arm. 12 is a bar similarly perforated, and 13, 13' are bolts co-operating with the yoke and bar to mount the yoke 1 and its insulators by embracing and clamping the cross arm 10. This method of mounting the device of my invention is desirable when distributing from

poles carrying numbers of open wires on cross arms, as the drop wires may be radiated from a point near the end of the cross arm, rather than from the pole, and thus more easily 5 avoid accidental contact with the open wires of the pole line.

In Fig. 5 I show a modified bracket, consisting of a piece of bar iron 14 shaped into a loop at 15, the free ends being bent outwardly 10 and perforated at 16. A pair of brackets of the type shown in Fig. 5 may be used to sustain the bolt or rod 17, the assembly being as shown in Fig. 6, in which 14, 14' are two such brackets, the rod 17 passing through 15 the insulators and through the openings 15 in the brackets 14, 14'.

The device of Fig. 6 may be assembled complete and subsequently mounted upon the pole, whereas in the exact type illustrated in the Figs. 1, 2 and 3, assembly upon 20 the pole is required, as the rod 6 would interfere with the lag screws 4, 4'.

I do not wish to limit my invention to the exact details herein shown and described. I 25 have illustrated but two of the many modifications possible.

What I claim as new and desire to secure by United States Letters Patent is:

In a distributing bracket, a U-shape member formed of a single piece of malleable iron 30 bent into shape and pierced with holes for bolts; a bolt passing through holes in the arms of said U-shape member and insulators supported upon said bolt; said U-shape member having a surface suitable for contact with 35 the surface of a pole when the bracket is mounted upon a pole, and having holes for bolts through the member and through said surface of the member, for attaching said member to the pole, said last mentioned holes 40 being spaced with a clear distance between two holes equal approximately to the thickness or height of a cross arm whereby said U-shape member is adapted to be mounted upon a pole by lag bolts or other bolts or 45 upon a cross arm by a pair of bolts or a yoke embracing the cross arm, substantially as described.

Signed by me at Terre Haute, county of Vigo and State of Indiana, in the presence 50 of two witnesses.

ALBERT L. STADERMANN.
